ELECTRIC SWITCH

Robert L. Gallup, Niles, Mich., assignor to McGill Manufacturing Company, Inc., Valparaiso, Ind., a corporation of Indiana

Original design application Oct. 18, 1968, Ser. No. 14,055.
Divided and this application June 9, 1969, Ser. No. 17,574.

Term of patent 14 years
Int. Cl. D13—03

U.S. Cl. D26—13

FIG. 1 is a perspective view of an electric switch showing my new design;

FIG. 2 is a side elevation view;

FIG. 3 is a front elevation view;

FIG. 4 is a rear elevation view; and

FIG. 5 is a perspective view of a modified form of the switch shown in FIG. 1.

This is a divisional application of application Ser. No. 14,055, filed Oct. 18, 1968 and assigned to the assignee of this application.

I claim:

The ornamental design for an electric switch, as shown and described.
